UNITED STATES PATENT OFFICE

WILLIAM B. HODGE, OF CHARLOTTE, NORTH CAROLINA, ASSIGNOR TO PARKS-CRAMER COMPANY, OF FITCHBURG, MASSACHUSETTS, A CORPORATION OF MASSACHUSETTS

THERMOSTATIC APPARATUS

Application filed April 23, 1929. Serial No. 357,460.

This invention relates to improvements in thermo-sensitive elements of the type commonly known in the art as "capsule elements", or diaphragm motors, suitable for the actuation of thermostatic apparatus.

Such elements are usually of annular form and consist of two walls of flexible metal rigidly attached together and hermetically sealed at their periphery. The diaphragm walls 10 are usually composed of thin metal sheets having means such as annular grooves or corrugations which are intended to increase the flexibility of the diaphragms so as to permit the greatest possible distortion by the pressure of the expansible fluid contained within the walls of the element.

Such elements are usually charged with a limited quantity of any suitable volatile fluid. The diaphragm walls are, therefore, subject 20 to the vapor pressure characteristic of the fluid at the temperature to which the element is exposed. As the temperature varies, the vapor pressure changes in accordance with the characteristics of the fluid and the resulting distortion of the walls is utilized to actuate suitable mechanism for indicating or registering the temperature of an enclosure, or for initiating the action of mechanism operable to control the temperature or the condition of humidity of the enclosure, or both. It is characteristic of those volatile fluids 30 which are commonly used for such purposes that as the temperature is increased, the pressure of the vapor increases not in direct proportion to changes in temperature, but at a rate which progressively increases.

The ordinary diaphragms commonly used for such purposes are provided with annular corrugations for the purpose of increasing 40 their range of axial distortion in response to changes in temperature. Since the vapor pressure of the volatile fluids in common use increases in rapid progression with respect to uniform increments of increase in temperature, there is in consequence a similar and considerable increase in the rate of axial distortion with respect to temperature, so that equal increments of increase in temperature are reflected in progressively increasing incre-

ments of distortion in the performance of ordinary diaphragms of this type.

Where such thermo-sensitive elements are used in instruments for indicating and recording temperatures, or for actuating mechanism to control temperature or the humidity of an enclosure, this progressively increasing expansion of the thermo-sensitive element is decidedly disadvantageous, and numerous attempts have been made to reduce or eliminate 55 it by the application of compensating devices, such as a spring so disposed with reference to the diaphragm as to subject it to progressively increasing resistance, or by the provision of devices for translating the variable 60 movements of the diaphragm, caused by uniform changes in temperature, into uniform movements. Such attempts have necessarily introduced many mechanical complications resulting in costly constructions which easily 65 get out of order and at best only produce approximately uniform movements correlated to uniform changes in temperature.

The principal object of the present invention is to produce a thermo-sensitive element 70 of the well-known diaphragm-motor type, whose axial expansion in response to increasing temperature shall be characterized by uniform increments of expansion in response to uniform increments of temperature—that 75 is to say, a diaphragm motor possessing a uniform coefficient of expansion throughout a predetermined temperature range.

In the present type of my invention, this is accomplished by making use of an element 80 comprising a closed receptacle for a volatile fluid having an elastic annular diaphragm wall or walls, of spherical form, subject to the vapor pressure of the fluid within, and operable to oppose progressively increasing 85 increments of resistance to axial distortion of said wall or walls, the said resistance being so correlated to the progressive rate of increase in the increments of vapor pressure produced by uniform increments of temperature 90 as to compensate for said progressive increase in pressure.

I have discovered that a thermo-sensitive element or cell with a confined volatile fluid and having oppositely disposed like dia-

phragm walls of thin sheet metal peripheral 5
ly united and re-enforced to provide a rigid
annulus, with the effective areas of the walls
circumscribed by said annulus expansible
spherically within a predetermined range,
and having such resilience as to offer pro- 10
gressively varying resistance to spherical ex-
pansion by the vapor pressure of the fluid
in direct proportion to and compensatory of
varying increments of vapor pressure pro- 15
duced by such uniform increments of tem-
perature, will result in uniform increments
of axial movement of the respective dia-
phragms in response to uniform increments
of temperature.

I have also discovered that a thermo-sen- 20
sitive element or cell confining a volatile fluid
and having oppositely disposed like dia-
phragm walls of thin sheet metal peripheral-
ly united to provide a rigid annulus, with
the effective areas of said walls circumscribed
by said annulus, initially flat, but 25
spherically distorted by the vapor pressure
of the fluid, behaves in accordance with a
law which causes it to function in the de-
sired manner above described.

Diaphragms of the preferred type herein 30
disclosed and described are embodiments of
these novel discoveries and do in fact func-
tion in the desired manner. When subject-
ed to uniform increments of temperature
they respond with uniform increments of
axial distortion and may, therefore, be prop- 35
erly described as having a uniform coefficient
of axial expansion with respect to tempera-
ture.

So long as the temperature is not suffi- 40
ciently high to produce pressures that will strain
the material, of which the diaphragm is
composed, beyond its elastic limit, the ele-
ment or cell will return to its initial condition
as temperature is reduced and will re- 45
peat its performance indefinitely without dis-
playing altered characteristics or permanent
set. The effective range of temperature for
such an element is bounded by the boiling
point of the fluid used on the one hand, and 50
on the other by the temperature at which the
resultant vapor pressure produces a strain in
the material of the diaphragm that ap-
proaches its elastic limit.

Diaphragms of the usual type with annu- 55
lar corrugations are commonly manufac-
tured by the well-known process of spinning,
and have been found to be characterized by
great variation in uniformity, which is due
to variable pressure of the spinning tool and
variations in the "flow" of the metal, as a re- 60
sult of said pressure.

Such diaphragms, therefore, are seldom or
never interchangeable, because of their va-
riable characteristics, and when assembling
them into actuating elements for thermo-
static instruments, careful calibration and
selection is necessary, so that the production

of units whose characteristics are suitable
for their purposes is a necessarily expensive
process.

Another object of the invention is to pro- 70
vide a diaphragm adaptable to inexpensive
production by pressing, in preference to the
more expensive and less easily controlled
method known as spinning, with the purpose
of attaining both economy of production and
improved uniformity and interchangeability 75
in the product, it being highly desirable that
the diaphragm motors as finally produced
shall have strictly uniform characteristics of
expansion and that any group assembly of
such diaphragm units shall have the same rate
of expansion and the same total expansion
within and throughout a given range of tem- 80
perature as any other group-assembly of like
units of the same number.

One important advantage of the present in- 85
vention is the absence of localized strains in
the diaphragm surfaces—a condition tend-
ing to increase the life of the diaphragm mo-
tor units under their ordinary duty. Corru-
gated diaphragms are necessarily subject to
localized annular stresses and strains between
the corrugations, and such diaphragms fre- 90
quently fail under duty, as the result of crys-
tallization and cracking of the metal on the
lines where such strains occur.

The diaphragms having the smooth spheri- 95
cal surface of my improved type, being free
from such localized strains, show a greatly in-
creased life when tested to destruction by al-
ternating application and release of pres-
sure.

I am aware that heretofore use has been
made in the thermostatic art of actuating ele-
ments, such as bars of expansible material,
which have uniform coefficient of expansion,
but the expansive movements of such elements
in the usual ranges of temperature to which
the same are subjected are practically micro-
scopic and are difficult to utilize mechani-
cally in thermostatic indicating, recording
and regulating instruments.

By the present invention fluid-actuated
thermo-sensitive elements are provided which
have a uniform coefficient of expansion
throughout the usual temperature range to
which such elements are subjected and which
produce very considerable and measurable
axial movements which can be readily utilized
to actuate the indicating, recording or regu-
lating mechanisms of the instruments in
which they are employed.

These and other objects and features of the
invention will more fully appear from the
following description and the accompanying
drawings and will be particularly pointed out
in the claims.

In the drawings:

Fig. 1 is a vertical sectional view of a sim-
ple form of thermo-sensitive element em-
bodying the invention;

Fig. 2 is a plan view of the same;

Fig. 3 is a view in vertical diametrical section showing in superposed relation the members of a thermo-sensitive element having oppositely disposed diaphragm walls, and 5 illustrating also the manner in which the same are assembled;

Fig. 4 is a vertical diametrical sectional view of a preferred form of thermo-sensitive element embodying the present invention; 10

Fig. 5 is a view, mainly in vertical section, 15 illustrating groups or batteries of thermo-sensitive elements embodying the present invention as employed in a regulating instrument operable by the wet and dry bulb temperatures of the air, and also showing the manner in which the regulator controls the supply of humidity of a typical moisture-supplying mechanism; and,

Fig. 6 is a detail view, partly in section, 20 of the valve illustrated in Fig. 5, through which the action of the regulator operates to control the supply of humidity to an enclosure.

Ordinary temperatures of factories, work 25 shops, schools, dwellings, etc., in which temperature indicating, recording and regulating instruments are used, or in which humidity regulating devices are employed, range from 30 approximately fifty-five degrees to one hundred and ten degrees, Fahrenheit.

The predetermined temperature range 35 within which the vapor of a volatile fluid may be utilized to actuate a thermostatic element of the diaphragm or capsule type is limited by practical considerations, as is well known in the art.

The upper limit of temperature must be 40 lower than any temperature which would generate pressures sufficient to strain the material of the diaphragms beyond its elastic limit.

The lower limit of temperature must be 45 slightly higher than the boiling point of the fluid.

These considerations apply with equal 50 force to diaphragms of the corrugated type and also to diaphragms of my improved type. An important advantage which diaphragms 55 of my improved type derive from my invention is that within a predetermined temperature range, limited as above described, they have a uniform rate of axial expansion as temperature increases, as will presently be shown.

In the case of any volatile fluid confined in 60 contact with its vapor at temperatures which exceed its boiling point, the relation between vapor pressure and temperature is such that the pressure exerted by the vapor increases progressively with increases in temperature.

That is to say, there is a progressive increase in the value of the increments in pressure produced by uniform increments of 65 temperature. Reference to the Smithsonian

Physical Tables will show for instance that ethyl chloride, a volatile fluid frequently used as the expansive medium in such thermo-sensitive elements, has at a temperature of 20 degrees C. a vapor pressure of 99.62 70 centimeters of mercury; at 25 degrees C., a vapor pressure of 118.42; at 30 degrees C., a vapor pressure of 139.90; at 35 degrees C., a vapor pressure of 164.32; and at 40 degrees C., 191.96.

A temperature increase of five degrees C. from 20 degrees to 25 degrees shows an increase in vapor pressure of 18.80; a five degree increase in temperature from 25 degrees to 30 degrees shows an increase in vapor 80 pressure of 21.48; a five degree increase in temperature from 30 degrees to 35 degrees shows an increase in vapor pressure of 24.42; and a five degree increase in temperature from 35 degrees to 40 degrees shows an increase in vapor pressure of 27.64.

Where a corrugated diaphragm is employed the flexibility of the diaphragm is such that the axial movement of the diaphragm produced by the progressively increasing vapor pressure is approximately proportional to the increase in vapor pressure.

If the elastic resistance to distortion of the diaphragm walls be constant or nearly 95 so, as in the case of ordinary corrugated diaphragms, it is clear that the axial distortions due to equal increments of temperature will reflect the progressive increase in vapor pressure increments by a similar progressive increase in increments of distortion, which is, in fact, true, as is well-known 100 in the art.

One of the distinctive characteristics of 105 my present invention is the peculiar property possessed by elastic diaphragms with smooth, spherical surfaces of my improved type, which, as I have discovered, oppose a progressively increasing resistance to distortion in response to increasing vapor pressure, the rate of increase in resistance being so correlated to the rate of increase in pressure as to compensate therefor, and thereby produce uniform increments of axial distortion in response to uniform increments of 110 temperature.

By virtue of this distinguishing characteristic, diaphragm motors of my improved type 115 therefore become possessed of a uniform coefficient of expansion throughout the predetermined range of temperature for which they are adapted.

I have also discovered that a diaphragm 120 of my improved type is equally effective for the purposes of my invention whether it has an initially spherical surface of slight curvature, or whether it be initially flat, since the surface of a flat diaphragm is distorted into a spherical form as soon as any sensible pressure is imposed upon it, and continues in a 125

spherical form, the curvature of the sphere increasing and the radius decreasing as the pressure is increased.

5 The ability to use initially flat diaphragms is another advantageous feature of my invention, since manufacture may be accomplished more conveniently and cheaply than when initially corrugated or curved surfaces are required.

10 In manufacturing units of this type, the volatile fluid is commonly cooled to freezing temperatures by the influence of a mixture of ice and salt, or some other suitable freezing mixture, and is then introduced into the 15 diaphragm elements which are subsequently sealed. Upon being subsequently exposed to higher temperatures than the boiling point of the fluid, vapor pressure as soon as generated will effect the initial distortion, which produces the desired spherical condition of the 20 diaphragm surface.

I have found that sheet metals of the stronger and more elastic alloys, such as 25 Phosphor bronze, are obtainable with such uniform thickness and elastic properties that diaphragm elements of my improved type manufactured from such material, when actuated by the vapor of ethyl chloride will consistently show an excellent performance characterized by all of the advantages above 30 described.

Discs cut or pressed from high-grade sheet metal for manufacturing this improved type 35 of diaphragm have proved to be so uniform that the completed diaphragms have uniform characteristics and to be interchangeable.

In the assembled groups of units, any assembly containing a given number of diaphragm elements is found to have the same 40 uniform rate of expansion and the same total expansion within usual ranges of temperature as any other assembly of the same number of units.

The advantage of uniformity and interchangeability in such units and the absence of all necessity for calibration and selection in assembling is an obvious advantage and results in great economy in manufacture.

45 A simple form of apparatus is illustrated 50 in Fig. 1 of the drawings which comprises a receptacle having a bottom or base 1 of preferably cylindrical form having an up-turned rigid peripheral flange 2 providing a chamber 3 for a volatile fluid, such as ethyl chloride. The receptacle is hermetically closed 55 by a diaphragm 4, preferably of circular form and of a diameter equal to the diameter of the base 1. It may be rigidly secured at its periphery to the flange 2 in any suitable manner, as for example by soldering, and the periphery thereof, which overlies the flange 2 re-enforced by a rigid ring 5 soldered to the periphery of the disk, and if desired also fixedly secured to the flange 2 by clamping 60 screws, or otherwise.

The diaphragm 4 may be made initially of slightly spherical form, as illustrated in Fig. 1, or it may be made flat and distorted to spherical form by the vapor pressure of the fluid contained in the closed receptacle. In either case a suitable amount of volatile fluid is introduced into the receptacle at a temperature below the lower limit of the range of 70 temperature to which the element is to be subjected.

75 In Figs. 3 and 4 a preferred embodiment of the invention is illustrated which comprises a closed receptacle for a volatile fluid having oppositely disposed diaphragm walls. In this construction the diaphragm walls are 80 of suitable elastic material, such as sheet bronze, and desirably are pressed to provide a flat effective area subject to the vapor pressure of the fluid, and an offset peripheral flange adapted when two of such diaphragms 85 are superimposed in reverse relation to provide a chamber for the volatile fluid between the diaphragms.

85 As illustrated in Fig. 3 the lower diaphragm has a circular flat central portion 6 with a continuous, slightly offset peripheral portion 7 and an upwardly bent annular flange or rim 8. The upper diaphragm has a central flat circular portion 9 with an integral offset peripheral portion 10 complementary to the offset portion 7 of the lower diaphragm, but of slightly smaller diameter and adapted to seat within the peripheral flange 8 of the lower diaphragm.

90 In assembling the diaphragms together the peripheral portions 10 and 7 desirably are hermetically secured together by solder 11 and the flange 8 thereupon bent down upon the upper face of the peripheral portion 10 of the upper diaphragm and soldered thereto, thereby providing a soldered lock-seam joint. Desirably a rigid re-enforcing ring 12 is provided which has a horizontal flange 13 and a vertical flange 14, the vertical flange 14 being of such diameter as to fit upon the 110 flange 8 of the lower diaphragm when its edge has been bent about the periphery of the upper diaphragm as above described, thereby providing a rigid annular peripheral 115 support for the diaphragm which is effectively resistant to radial contraction or expansion in response to variations in the tension imposed upon the ring by the diaphragms due to the expansion and contraction of the vapor of a volatile fluid when subjected to different temperatures. The horizontal flange 14 is thereupon bent around and clamped upon the periphery 7 of the lower diaphragm, as illustrated in Fig. 4.

120 The ring 12 desirably is also soldered to the peripheral portions and flanges of both diaphragms. The soldering together of the parts above described may be conveniently accomplished by tinning sufficient area of one or both of the contacting parts, so that when 125 130

such parts are heated and pressure applied thereto the tin will melt and form the soldered joint. The diaphragms thus assembled are peripherally united to provide a rigid 5 annulus circumscribing circular effective areas which are expansible spherically within in a predetermined range and produce uniform amounts of axial movement by elastic resistance compensatory of the varying 10 amounts of vapor pressure of the confined fluid which result from uniform amounts of temperature variation.

The central portions of the diaphragms desirably are provided with rigid circular members 15 of relatively smaller diameter by which the axial movements of the diaphragms may be transmitted to the usual indicating, recording or regulating mechanisms. Desirably the rigid central members are in the 20 form of couplings by which the elements may be mounted or assembled in groups.

In the construction illustrated in Fig. 4 the expansible portion 6 of the lower diaphragm has secured centrally to it a cup-shaped coupling member 15 having a tubular stud 16 which extends through the central aperture in the member 6. A washer 17 fits around the stud 16 and the edge 18 of the stud is spun tightly down upon it, thereby clamping the 25 coupling member 15 firmly to the diaphragm. The cup-shaped coupling member 15 is provided with internal screw threads 19 adapted to fit complementary external screw threads upon the coupling member which is secured 35 to the opposite or upper diaphragm.

The coupling member of the upper diaphragm comprises a head 20 having external screw threads 21 complementary to the screw threads 19 and a central tubular stud 40 22 which extends through and fits the circular aperture in the expansible portion 9 of the upper diaphragm. The washer 23 fits upon the stud and the edge 24 of the stud is spun down upon the washer, thereby clamping 45 the coupling firmly to the upper diaphragm.

Hermetic sealing of the parts of the coupling members to the diaphragms may be insured by soldering them together in the manner above described.

The coupling member 20 of the upper diaphragm desirably is provided with a central aperture 25 having a screw threaded wall adapted to permit the introduction of volatile 55 material into the chamber 26 of the element and which thereafter may be filled with a screw threaded plug, (not shown), and hermetically sealed by solder.

It is found that the presence of the central re-enforcing disks or couplings have no appreciable effect upon the uniformity of axial movement of the diaphragms in response to uniform changes in temperature throughout the predetermined range above 60 stated.

The uniform radial or axial movement of the diaphragm of a thermo-sensitive element, such as above described, embodying my invention, which is proportional to uniform changes in temperature is advantageous even 70 in the construction of a simple thermostat, since the dials with which all such thermostats are equipped can be calibrated in uniform graduations and the adjusting mechanism of each thermostat set so that any instrument will fit the standard dial. 75

A greater advantage, however, is derived from the use of thermo-sensitive elements embodying the invention in differential thermostats which are more familiarly known 80 as wet and dry bulb hygrometers widely used for automatic control of the condition of humidity of the air of an enclosure.

A typical instrument of this class is illustrated in Fig. 5 together with the means operable thereby for regulating the amount of moisture delivered to the enclosure. 85

As illustrated in Fig. 5 the instrument comprises a casing 27, preferably of rectangular form, having a horizontal partition 28 a short distance from its upper end and a vertical partition 29 dividing the lower portion into a dry bulb chamber 30 and a wet bulb chamber 31 of approximately equal size. Air is permitted to enter the dry bulb chamber through 90 a screened opening 32 in the bottom thereof and the partition 29 is provided with an aperture 33 through which the air may pass from the dry bulb chamber to the wet bulb chamber. An opening 34 in the lower portion of 95 one of the side walls of the wet bulb chamber permits the escape of the air from the wet bulb chamber. A spray head or atomizer 35 is provided in the upper compartment 36 of the instrument and projects the spray downwardly into the wet bulb compartment 31, thereby causing the circulation of a sample of 100 the air of the enclosure, in which the instrument is located, upwardly through the dry bulb chamber, thence downwardly through 105 the wet bulb chamber in which it is saturated and reduced to the psychrometric temperature 110 thereof.

Similar groups or batteries of thermo-sensitive elements are provided in each of 115 these chambers. As illustrated, the wet bulb member comprises four thermo-sensitive elements 37 of the character illustrated in Fig. 4, the exposed coupling member 38 of one of the outside members being mounted upon the stem of an adjusting screw 39 which has a screw threaded portion engaging the wall of the casing. The exposed coupling 40 of the outside thermo-sensitive member is pivotally connected to the lower arm 41 of a lever 42 which is pivotally mounted upon a bracket 43 of the casing. The upper end of the arm 42 extends through a suitable aperture in the partition 28 of the casing into the upper chamber 36 thereof. The lower end of 120 125 130

the arm 41 of the lever is connected by a spring 44 to an arm 45 which is mounted upon the adjusting screw 39 and serves to hold the lower end of the lever arm in contact with the thermo-sensitive members during the contractive movements thereof.

The dry bulb thermostatic member of the instrument is similarly constructed and comprises a battery 46 of four thermo-sensitive elements, the coupling member 47 of one of the outer elements being mounted upon a stud 48 extending from the partition wall 29 and the coupling member 49 of the other outside element being pivotally connected to the lower arm 50 of a lever which is fulcrumed upon a bracket 51 upon the casing. The upper arm 52 of the lever extends through a suitable aperture in the casing 28 and is provided at its upper end with a shelf 53 forming a valve seat and having a port which preferably is in the form of a narrow rectangular slot. A pipe 54 of flexible material communicates with this port and with the chamber of a diaphragm relay valve as will be herein-after more fully described.

A valve 55 is slidably mounted upon the valve seat 53 and is connected by a link 56 with the upper end of the lever arm 42.

In the operation of the device the differential movement of the lever arms 42 and 52, caused by unequal expansive movements of the wet and dry bulb thermostatic members, will actuate the valve 55 either to the open position illustrated in Fig. 5, or to closed position in which the port for the pipe 54 will be covered. This movement of the valve is utilized to govern pressure of the diaphragm motor of a relay valve which in turn governs the pressure of a diaphragm motor 40 which actuates a valve for controlling the supply of moisture to the air of an enclosure.

In the construction illustrated air under pressure is supplied through a pipe 57 having a branch 58 provided with a restriction 59 through which air under pressure is supplied to the pipe 54 leading to the port of the valve seat 53. A branch 60 from the pipe 54 leads to the chamber of a diaphragm motor 61 of a relay valve.

The relay valve is illustrated in detail in Fig. 6 and comprises a body 62 having at its outer end a chamber 63 which is closed by a screw threaded plug 64. A relatively small bore 65 leads from the chamber 63 to a chamber 66 in axial alignment therewith.

The ends of the bore 65 provide seats for a conical valve 67 the stem 68 of which engages the central portion of the diaphragm 69 of the motor and a helical spiral spring 70 surrounding the valve stem 68 normally acts to maintain the valve in open position illustrated in Fig. 6. A small rod 71 is seated in and extends axially from the valve 67 through the bore 65 and at its opposite end engages a conical valve 72 which is normally held in

seated position by a spring 73 in the chamber 63. The pipe 57 is provided with a branch 74 which leads to the chamber 63 and a port 75 leads from the bore 65 to a pipe 76 which in turn leads to the chamber of a diaphragm motor 77. The diaphragm 78 of this motor engages centrally the stem 79 of a valve (not shown) which controls the supply of air through a pipe 80 to an atomizer or series of atomizers 81 which are supplied with water from a pipe 82 in which the head of water is maintained slightly below the level of the atomizer. Any suitable number of atomizing devices may be employed for an enclosure as is well known by the those skilled in the art.

In the preliminary setting of the device the adjusting screw 39 is set to provide a predetermined wet bulb depression that is to say at a certain temperature difference between the wet and dry bulb thermostatic members as to cause the valve 55 to open the port in the valve seat 53 when a predetermined difference in temperature between the wet and dry bulb thermostatic elements is reached.

Air under pressure is supplied to the pipe 57 and passing through the restricted ports 59 of the branch 58 will build up a pressure in the pipe 54 if the valve 55 is in closed position. However, the instrument is usually set so that the valve 55 will not close the port leading to the pipe 54 when the humidity equals or exceeds the predetermined desired humidity.

In the operation of the device if the humidity of the enclosure exceeds a predetermined humidity and the temperature rises and falls without substantial change in the humidity, the lever arms 42 and 52 will be actuated in the same direction and with substantially equal movements and the valve will remain in open position. If, however, by reason of decrease of humidity the expansive movement of the wet bulb member, due to the more rapid evaporation of the moisture upon the surface thereof, exceeds that of the dry bulb member a differential movement of the lever arms 42 and 52 will be produced which will move the valve 55 to closed position, thereby preventing the escape of air from the pipe 54 and causing the pressure to be built up in said pipe and in the chamber of the diaphragm motor 61, so that the diaphragm 69 will force the valve 67 to closed position, thereby causing the rod 71 to open the valve 72 and permit air under pressure to pass from the pipe 57 through the pipe 74, the chamber 63, the bore 65 and passage 71 into the pipe 76 and to the chamber 77 of the main diaphragm motor. As the pressure builds up in the chamber of the diaphragm motor 77 the valve stem 78 will be actuated to open the valve in the compressed air line 80, thereby causing the actuation of the atomizers 81.

When the predetermined degree of humidity has been attained the relative movement of the lever arms 52 and 42 will be such as again to move the valve 55 to open position, thereby relieving the pressure in the pipe 54 and permitting the springs 70-73 to restore the valves 67 and 72 to normal position, thereby cutting off the supply of air through the pipe 74. The body 62 of the relay valve 10 is provided with a port 83 leading to the chamber 66 so that when the valve 67 is restored to open position by the springs air is permitted to escape from the chamber or the diaphragm motor 77 through the pipe 76, the bore 65, chamber 66, and exhaust port 83, thereby permitting the spring 79 again to close the valve in the compressed air pipe 80 and discontinue the action of the moisture-supplying means.

20 Of course, regulators of this character are well known in the art and are used for regulating various other types of moisture supplying mechanism.

25 Wet and dry bulb thermo-sensitive elements provided with the old form of corrugated diaphragms having a variable rate of expansion at different temperatures can be made to function properly to control humidity only within limited wet bulb depression 30 adjustments. Where it is necessary that the instrument be adapted to control different percentages of relative humidity only approximately accurate results can be secured as the ratio between the wet and dry bulb 35 indications is not the same at the low temperature scale as at a high temperature scale. This fact has long been recognized by those skilled in the art as involving an error inherent in vapor pressure instruments and various expedients have been resorted to to minimize this error, all of which have been costly and none strictly accurate. A change of one degree in either 40 the wet or dry bulb temperature corresponds to a change of from three to four per cent in relative humidity; consequently, for close humidity regulation at high and low temperatures it is necessary that the relative movements, caused by the relative 45 expansion of the wet and dry bulb members, shall be accurately co-ordinated to secure the desired result and it is desirable that the instrument shall have a sensibility of at least one-fourth to one-half degree F. to maintain 50 a desired predetermined substantially constant condition of humidity. This, which has been very difficult of accomplishment in instruments heretofore produced, is readily accomplished in instruments having thermo-sensitive elements embodying the present invention without the necessity of introducing corrective and adjusting mechanisms and the numerous disadvantages resulting therefrom.

55 It will, therefore, be obvious that by the

present invention I have provided a thermo-sensitive element which can be manufactured more economically and with greater uniformity than similar elements which have heretofore been produced; that such elements are capable of being embodied in thermostatic indicating and recording instruments with greater facility by reason of the elimination of the unequally graduated dials and the necessity for calibrating each instrument, and that such elements may be employed in regulating devices particularly those of the wet and dry bulb hygrometric type to produce movements of the mechanisms thereof with greater accuracy than has heretofore been accomplished and to provide means whereby the instrument will respond properly throughout the predetermined temperature range at any wet bulb setting.

It is to be understood that the particular embodiments of the invention disclosed herein are of an illustrative character and are not restrictive of the meaning and scope of the following claims.

Having thus described the invention, what is claimed as new, and desired to be secured by Letters Patent, is:

1. A thermo-sensitive cell with a confined volatile fluid having oppositely disposed like diaphragm walls of initially flat, thin sheet metal peripherally united to provide a rigid annulus, with the effective areas of said walls circumscribed by said annulus, primarily distorted to slightly spherical form and expansible spherically within a predetermined temperature range by the vapor pressure of the fluid and producing uniform amounts of axial movement throughout said temperature range corresponding with uniform changes in temperature by virtue of variations in the elastic resistance that is characteristic of said walls and compensatory of the variation of the changes in vapor pressure that is characteristic of the confined fluid when subjected to uniform changes in temperature.

2. A thermo-sensitive cell with a confined volatile fluid having oppositely disposed like diaphragm walls of initially flat, thin, sheet metal, peripherally united to provide a rigid annulus with the effective areas of said walls circumscribed by said annulus spherically distorted by the vapor pressure of the fluid expansible spherically within a predetermined temperature range and producing uniform amounts of axial movement throughout said temperature range corresponding with uniform changes in temperature by virtue of variation in the elastic resistance that is characteristic of said walls and compensatory of the variation of the changes in vapor pressure that is characteristic of the confined fluid when subjected to uniform changes in temperature.

3. A thermostatic motor consisting of a plurality of like thermo-sensitive cells each

having oppositely disposed initially flat diaphragm walls of thin sheet metal peripherally united to provide a rigid annulus and confining a volatile fluid with the effective areas circumscribed by said annulus expansible spherically within a predetermined temperature range and producing uniform amounts of axial movement by elastic resistance compensatory of the varying changes in the vapor pressure of the confined fluid which result from uniform changes of temperature and means coupling the central portions of adjacent diaphragms in axial alinement thereby to cause the resultant axial movement of said cells to be directly proportional to the variations in temperature to which said motor is subjected.

4. A regulator comprising thermostatic motors subject respectively to the wet and dry bulb temperatures of the air, each motor consisting of a plurality of thermo-sensitive cells having the same coefficient of expansion and interchangeable with any other cell of the same or another motor of said regulator, each cell comprising initially flat diaphragm walls of thin sheet metal peripherally united to provide a rigid annulus with the effective areas of said walls circumscribed by said annulus, confining a volatile fluid and expansible spherically within a predetermined temperature range, and producing uniform amounts of axial movement by elastic resistance compensatory of the varying changes in the vapor pressure of the confined fluid which result from uniform changes in temperature, and means detachably coupling the central portions of the contiguous diaphragms of successive cells of each motor in axial alinement to provide a structure in which the combined axial movement of the respective motors is directly proportional to variations in the temperature to which they are respectively subjected.

In testimony whereof, I have signed my name to this specification.

WILLIAM B. HODGE.
